UNITED STATES PATENT OFFICE.

RALPH IRWIN HENDERSON, OF CHARLESTON, WEST VIRGINIA,

TOOL.

Application filed January 3, 1928. Serial No. 244,235.

This invention aims to provide novel means whereby a charge of explosive may be deposited in a well.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in longitudinal section, a device constructed in accordance with the invention, parts being in elevation;

Figure 2 is a fragmental elevation showing the lower portion of the receptacle and attendant parts;

Figure 3 is a bottom plan.

The device forming the subject matter of this application preferably is made of metal, and includes a tubular receptacle 1, embodying a barrel 2. A suspension bail 3 extends downwardly within the upper end of the barrel 2 and is held upon the barrel, removably, by means of a securing device, such as a bolt 4, mounted in the lower end of the bail 3 and in the upper end of the barrel 2. A tubular foot 5 is provided, and the lower end of the barrel 2 extends downwardly within the upper end of the foot 5. Securing members 6, such as screws, hold the foot 5 on the lower end of the barrel 2. The foot 5 is provided with an internal shoulder 7, against which the lower end of the barrel 2 abuts, so as to take some of the strain off the screws or securing elements 6. The tubular foot 5 is considerably thicker than the barrel 2. This construction is resorted to in order to add weight, and to provide a secure place of mounting for sundry movable parts which will be alluded to hereinafter. The foot 5 is provided in its lower end with a notch 8, and a pivot element 9 extends across the notch 8, the pivot element being mounted at its ends in the foot 5. A notch 10 is formed in the lower end of the foot 5 and is disposed opposite to the notch 8. The notch 10 communicates with a superficial longitudinal groove 11 formed in the

outer surface of the foot 5 and extended longitudinally of the foot. A seat 12 is fashioned in the foot 5 and communicates with the longitudinal groove 11 at a point near to the lower end of the groove.

The numeral 14 designates a retainer, in the form of a bar. One end of the retainer 14 extends into the notch 8 and is mounted on the pivot element 9, the construction being such that the retainer 14 may swing from the solid line position of Figure 1 to the dash line position of that figure. The retainer 14 is provided intermediate its ends with a depending projection 15. That end 70 of the retainer 14 which is remote from the pivot element 9 extends into the notch 10 and is provided with a hook-shaped part 16, the bill of which depends.

The numeral 17 designates a latch extended longitudinally of the tubular foot 5, and located in the groove 11. The latch 17 is mounted movably at a point intermediate its ends, upon a fulcrum member 18, such as a headed screw threaded into the foot 5 at the base of the groove 11. The construction is such that the latch 17 can tilt in the direction of its length on the fulcrum member or screw 18, but the latch 17 cannot swing laterally on the fulcrum member or screw 18, because the latch is held by the head of the screw 18, in the longitudinal groove 11. In the upper end of the latch 17 is mounted an adjustable stop 19, such as a screw, adapted to engage the foot 5 at the base of the groove 11. The screw 18 may be threaded in or out, as occasion may require, to limit the amount that the latch 17 tilts. It is desirable to limit the amount that the latch 17 tilts, so that the lower end of the latch will not swing outwardly, or to the left in Figure 1, too far and catch on external objects. A compression spring 20 is mounted in the seat 12 and bears against the latch 17 at a point adjacent to the lower end of the latch. On its extreme lower end, the latch 17 is supplied with a hook-shaped part 21, the bill of which extends upwardly, for engagement with the depending bill on the part 16 of the retainer 14.

In practical operation, the retainer 14 is raised into the horizontal position of Figure 1, and the hook-shaped part 16 of the retainer 14 is engaged with the hook-shaped 21 of the latch 17. The latch 17, thus, is prevented from swinging outwardly at its lower end, under the impulse of the spring

20, which is under compression. The securing element or bolt 4 is removed, together with the suspension bail 3, and the charge 22 is placed in the barrel 2. The securing element 4 and the suspension bail 3 then are replaced, and the device appears as disclosed in solid line in Figure 1 of the drawings.

Charges of explosive generally are deposited in an oil well in comparatively small slugs, like the member 22, and these elements 22 are lowered one at a time. When the device, arranged as shown in solid line in Figure 1 of the drawings, has been lowered 15 far enough into the well, the projection 15 on the retainer 14 comes into contact with the charge, which has already been deposited in the well, and owing to the weight of the device shown in Figure 1, the receptacle 20 1 moves downwardly with respect to the retainer 14, and the hook-shaped part 16 of the retainer 14 is disengaged from the hook-shaped part 21 of the latch 17. The latch 17, then, can swing outwardly at its lower end, responsive to the action of the spring 20, and if the device be raised a little, the retainer 14 will swing down into the dash line position of Figure 1; and the charge 22 can be eased down into the well. The device 25 30 then is withdrawn and the process described

is repeated, until the desired amount of explosive has been deposited in the well.

What is claimed is:—

1. In a device of the class described, a receptacle, a pivoted retainer extended across the receptacle, a latch mounted movably on the receptacle, interengaging parts on the latch and on the retainer, the retainer being upwardly movable to disengage said interengaging parts when the retainer rests on an object, and spring means for moving the latch to hold said interengaging parts clear of each other, after they have been disengaged as aforesaid. 35

2. In a device of the class described, a receptacle, a pivoted retainer extended across the receptacle, a latch mounted movably on the receptacle, interengaging parts on the latch and on the retainer, the retainer being upwardly movable to disengage said interengaging parts when the retainer rests on an object, spring means for moving the latch to hold said interengaging parts clear of each other, after they have been disengaged as aforesaid, and adjustable means for 40 45 50 limiting the movement of the latch.

In testimony that I claim the foregoing as my own, I have hereto affixed my signature.

RALPH IRWIN HENDERSON.
